UNITED STATES PATENT OFFICE.

SAMUEL SEGAL, OF NEW YORK, N. Y., ASSIGNOR, BY MESNE ASSIGNMENTS, TO SEGAL AUTOMATIC TWEEZER CORPORATION, OF NEW YORK, N. Y., A CORPORATION OF NEW YORK.

SAFETY RAZOR AND STROPPING DEVICE.

Application filed July 6, 1925. Serial No. 41,503.

This invention relates to a safety razor and a blade-stropping device, both presenting improved constructions and particularly adapted for use in combination with each other.

- 5 It is an object of the invention to provide a device which will efficiently perform the purposes for which it is intended, and which will also be economically and readily manufactured and easily assembled.
- 10 A further object resides in the provision of a safety razor of improved construction which will be well-balanced and readily manipulated, and the parts of which may be cleansed with facility.

- 15 A still further object is that of providing a stropping device particularly adapted to be employed in connection with a safety razor of the type subsequently suggested, and which may be readily used in sharpening and conditioning a blade to a point where it will give most satisfactory results.

- Another object is that of furnishing a razor of such construction that the blade will shave more efficiently, and in which this blade will 25 be protected so that the danger of accidents will be reduced to a minimum.

- With these and further objects in mind, the invention accordingly comprises the features of construction, combination of elements, and 30 arrangement of parts which will be exemplified in the construction hereinafter set forth, and the scope of the application of which will be indicated in the claims.

- For a fuller understanding of the nature 35 and objects of the invention reference should be had to the following detailed description taken in connection with the accompanying drawings, in which:

- Fig. 1 is a front elevation of one form of 40 razor embodying the improved construction of the present invention;

Fig. 2 is a side elevation thereof;

Fig. 3 is a perspective view of the guard;

- 45 Figs. 4, 5 and 6 are views corresponding to Figs. 1, 2 and 3 respectively, and showing a somewhat different form of razor from that shown in the preceding figures;

Fig. 7 is a front elevation of a further form of razor;

Fig. 8 is a sectional side view thereof;

Fig. 9 is a perspective view of one of the structural details forming a part of the razor shown in the two preceding views;

Fig. 10 is a side elevation of still another

form of razor, with the guard swung into in- 55 operative position;

Fig. 11 is a similar view, with the blade-supporting yoke removed, and the guard in operative position;

Fig. 12 is a rear view of the razor as shown 60 in Fig. 10;

Fig. 13 is a fragmentary and enlarged plan view of a guard of the type shown in Figs. 10 and 11;

Fig. 14 is a plan view of a razor blade which 65 may be employed in connection with any of the forms of razors previously referred to;

Fig. 15 is a partly sectional plan view of a blade and bladeholder which may be like- 70 wise employed;

Fig. 16 is a partly sectional side view of the 75 elements as shown in Fig. 15;

Figs. 17, 18 and 19 are side elevations of forms of stropping devices which may be em- 80 ployed in conjunction with these razors for sharpening and conditioning blades associated therewith;

Fig. 20 is a fragmentary front elevation of 85 a razor, with a blade-restraining element in association therewith; and

Fig. 21 is a sectional side view of the mech- 90 anism as shown in Fig. 20.

Referring primarily to the razor, it will be noted that the reference numeral 20 indicates the handles of these devices, these handles in the present instance supporting at their upper ends yokes 21, the arms 22 of which have their outer ends extending beyond the handles a distance in excess of the width of the blade. 95

In each form of razor a shaft 23 is rotatably mounted between the upper ends of these arms, and this shaft, particularly as has been shown in Figs. 15 and 16, may carry a gear 24 and a bladeholder or retaining device. The latter preferably includes a body 25 provided with portions 26 extending around and fixedly secured to the shaft 23, this body being further extended to provide a tongue 27 formed with an inwardly-struck portion 28 in line with an opening 29 formed in the main portion of the body. The latter is also provided, if desired, with outwardly-struck portions 30, which, when a blade of the character shown in Figs. 14 and 15 is employed, 100 extend into notches 31 formed in the rear edge of this blade and thus prevent a sidewise dis- placement of the latter. 105

It will furthermore be noted that the blade body 32 is formed with an opening 33, and has its side edges recessed to provide shoulders 34 adjacent its cutting edge, the corners 5 between these side edges and this cutting edge being preferably rounded as at 35.

Thus it will be apparent that the blade is simply grasped and shoved between the body 25 and the tongue 27, in which position it is 10 retained incident to the fact that the inwardly-struck portion 28 of the tongue will enter through the opening 33 and extend into the opening 29, and furthermore, as aforesaid, for the reason that the extensions 30 15 will ride within the notches 31.

With reference to the type of razor shown in Figs. 1 to 3 it will be observed that the guard is swingingly secured to the yoke or fork 21. This guard conveniently includes a 20 plate 36 presenting a comb 37 at its outer edge, the teeth of which, as in the usual manner, extend outwardly, the end teeth 38, however, extending inwardly for a purpose hereinafter brought out. The ends of the plate 36 25 are extended at right angles to the body thereof, so that a U-shaped member is provided. These ends 39 have their lowermost portions pivotally secured as at 40 to the lower ends of the arms 22, and are extended 30 and provided with inwardly-struck portions 41, which engage with the rear edges of the razor yoke when the guard is in its normal position, as has been shown in all of the figures referred to.

With the shaft 23 in position it will be understood that, as previously brought out, the blade will be prevented from relative movement with respect thereto, and if the guard is 40 in the position shown in the figures referred to the cutting edge of the blade will lie adjacent the outer ends of the teeth of the comb 37, the shoulders 34 of this blade being engaged by the rearwardly-extending teeth 38 of the comb so that relative movement between these 45 parts is also prevented. It will be equally obvious, however, that by simply pressing the rear ends of the elements 39 outwardly the inwardly-struck portions 41 which clear the rear edges of the yoke and the guard may be 50 swung with respect to the handle to a point at which the cutting edge of the blade clears this guard, and the blade body may be freely rotated between the arms of the yoke.

The construction shown in Figs. 4 to 6 is, 55 in all respects, similar to that shown and described in connection with Figs. 1 to 3, with the exception that instead of the inwardly-struck portions 41 one of the arms of the guard is provided with an arcuate slot 42, and the corresponding arm 22 of the razor yoke 60 carries a lock nut 43 mounted upon a screw-threaded shaft 44 and adapted to be tightened so as to bear against the outer face of the fork arm in order to clamp the same into 65 position and prevent relative movement.

Due to this construction, in addition to the fact that the parts are properly supported and the guard may be freely swung to inoperative position, the position of this guard may be accurately adjusted so that the cutting 70 edge of the blade is disposed in exactly the relationship desired to the comb of the guard.

In Figs. 7, 8 and 9 the handle 20 is screw-threaded adjacent its upper end as at 45, and a collar 46 is mounted upon these threads and is of a width slightly less than the length of the threaded portion. The guard is U-shaped, but the arms 47 thereof extend a substantial distance beyond the pivots 40, and, in fact, below the base of the yoke 21.

Interposed between the collar 46 and the yoke base is a plate 48, of a length slightly greater than the length of this base and provided with clips 49 engageable with the side edges thereof. It is obvious that with the 85 collar tightened the plate 48 will have its ends firmly bear against the extended portions of the arms 47 in order to prevent relative movement of the blade and guard. However, if the collar is loosened the intimacy of contact 90 between the plate and the arm portions aforementioned will be reduced, and, consequently, the guard may be adjusted, or the guard may be moved to wholly inoperative position so that the blade may be swung in the manner 95 aforesaid.

Thus, in the constructions shown in Figs. 4 to 9 inclusive, it is not alone practicable to normally retain the guard against movement and to move the same to a position at which 100 the blade may be swung through the fork or yoke, but, also, the position of the guard may be adjusted to relatively project or retract the cutting edge of the blade to any desired position. However, it is obvious that various forms of mechanism might be employed 105 to advantage in order to accomplish this result.

In the form of razor shown in Figs. 10 to 13 inclusive, the guard is provided by utilizing a guard-plate 50 having a comb 51 at its outer edge, the end teeth of this comb extending inwardly as at 52. The plate 50 is continued in the form of a shank 53 extending downwardly and terminating in a handle 54, 110 its central portion extending inwardly as at 55 and across the upper end of the handle 20. At this point it is pivotally secured to the handle by means of a pin 56, which also extends through a second downwardly- and inwardly-extending portion 57 forming a part 115 of the plate.

Normally, the guard is retained in the position shown in Figs. 11, 12 and 13 by means of a collar 58 slidably mounted upon the handle 120 20 and of an inner diameter sufficient to accommodate the handle 54 and prevent movement of the same with respect to the first-named handle. However, if desired, the collar 58 may be swung downwardly, as in Fig. 130

10, and the guard moved to inoperative position, in which, obviously, the blade may be swung through and around the yoke attached to the upper end of the handle 20.

5 Referring to the stropping device, it will be observed, as in Fig. 17, that a strop 59 of any desired material is employed, and mounted upon this strop is a traveler including a U-shaped plate 60, the body of which extends 10 below the strop, and the arms adjacent the side edges thereof and above the upper surface of the same. In order to retain the traveler in this position, and also to anti-frictionally guide the same, a pair of rollers 15 61 extends between its arms and bears against the lower strop face, while a further roller 62 bears against the upper face of the strop and lies in a position between the rollers 61. The upper arm ends of the traveler are pref- 20 erably notched as at 63 so as to accommodate the ends of the shaft 23; and it will be obvious that with the shaft in this position side- 25 wise movement of the razor with respect to the traveler will be prevented, and that if one of these elements is moved the other will move in unison therewith. Also, if the gear 30 24 is associated with the shaft 23, and a gear 64 is associated with the shaft of the rollers 62, these gears will mesh so that any tendency 35 of the roller 64 to turn will be transmitted to the shaft 23.

Thus it will be apparent that if the guard of a razor is swung to inoperative position, and the shaft thereof is moved to a point at 40 which its ends extend into the notches 63, any subsequent movement imparted to the traveler, as, for example, by exerting a pushing and pulling action upon the handle 20 of the razor, will necessarily result in these elements 45 traveling as one unit and in the roller 62 tending to turn. The direction of this turning tendency will vary according to the direction in which the traveler is moved, but, in any event, it will be appreciated that due to 50 the fact that the shaft 23 and the shaft of the roller 62 are coupled, as, for example, by the gears 24 and 64, the shaft of the razor will be turned to a point at which the cutting edge of the blade will bear against the upper surface 55 of the strop and will feather over the same. Obviously, a small number of movements on the part of the traveler and razor will result in the blade being excellently sharpened and conditioned, and the strop need not necessarily be held taut by virtue of the fact that the edge of the blade will bear against the upper face of the same substantially in line with one of the upper edges of the rollers 61.

In the form of stropping device shown in 60 Fig. 18 a U-shaped plate 65 similar to the plate 60 is employed, but in this instance the traveler carries merely a pair of rollers 66 and 67, the upper of which may support a gear 68 to cooperate with the gear 24 of the shaft 65 23,—conceding that the latter gear is used.

If desired, and as has been illustrated in Fig. 19, in lieu of a strop such as has been previously described a rigid support 69 may be employed. This support may, if desired, form the top or body of the box in which the 70 razor is sold, and may have its opposite faces covered by strips 70 and 71 presenting, for example, honing and stropping surfaces, respectively. Travelers, generally indicated at 72, may be mounted upon the support 69 so 75 that the razor may be applied with facility to either of the strips 70, 71.

Finally, if it is desired to present a turning of the blade when the guard is in inoperative position, the desired result may be accomplished, as has, for example, been illustrated in Figs. 20 and 21, by simply associating a spring 73 with the razor yoke and bearing against the blade-supporting shaft. Obviously, the frictional contact between this spring and 80 shaft will prevent a turning of the latter, but upon the razor being applied to the stropping device this will in no wise interfere with the proper operation of the parts.

In all of the forms of razors illustrated it 90 will be apparent that a user may readily employ the razor to advantage, and that the portions of the face which are relatively inaccessible in using the ordinary type of razor may be readily reached by any of the devices as 95 herein illustrated, in that the entire length of comb will be covered by the cutting edge of the blade. Furthermore, due to the fact that the corners of the latter are rounded, but little danger will exist of a person accidentally 100 inflicting a cut, and this will further be guarded against by virtue of the rigid manner in which the blade is normally secured against movement with respect to the razor parts.

When desired, the guard is readily movable 105 to inoperative position, and the razor may be applied with facility to the strop, which, by means of the razor handle, may be manipulated back and forth over the sharpening surface in order to properly condition the 110 blade; and immediately upon the sharpening operation being completed the parts may be swung to their normal position and the razor will again be ready for use.

Thus, among others, the objects aforementioned are accomplished, and since certain changes may be made in the above construction, and different embodiments of the invention could be made, without departing from the scope thereof, it is intended that all matter contained in the above description, or shown in the accompanying drawings, shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A safety razor, including a handle, a yoke secured thereto, a shaft rotatably mounted between the ends of said yoke, a blade secured to said shaft, means providing a guard for said blade and a spring attached to said yoke and frictionally bearing against said shaft to maintain the position of said blade.
2. A safety razor, including a handle, a guard secured thereto, said guard comprising a body presenting a plurality of outwardly-extending teeth at its edge, a blade connected with said handle and having its cutting edge in the plane of said teeth, rearwardly-extending portions forming a part of said guard at a point short of the plane into which said teeth extend, and said blade being formed with recesses at a point correspondingly short of its cutting edge, such extending portions projecting into the recesses of said blade.
3. A safety razor, including a yoke, a single shaft rotatably supported between the ends of said yoke, a blade connected with said shaft and swingable through the yoke, a guard associated with said yoke and cooperating with said blade, and means directly fixed to said shaft and engageable with a surface into which said razor may be brought into contact whereby to swing said blade with its cutting edge opposed to the direction of movement of the razor with respect to said surface.
4. A safety razor, including a handle, a blade, a yoke associated with said handle and connected with said blade to permit the latter to move between the arms of said yoke, and a guard comprising a U-shaped member having the outer portion of its ends pivotally connected with said yoke, and outstruck portions formed on said guard and engaging the rear edges of said yoke for preventing relative movement of the parts.
5. A safety razor, including, in combination, a handle, a blade, a yoke secured to said handle and mounting said blade between its outer ends, the depth of said yoke being sufficient to permit said blade to swing between

the arms thereof, a U-shaped guard pivotally secured to said yoke and having its body to one side thereof and engaging with said blade to normally prevent movement of the latter, a portion of said guard being extended to the opposite side of said yoke and engaging the rear edge thereof to normally prevent movement of said guard.

6. A safety razor, including, in combination, a handle, a blade, a yoke secured to said handle and mounting said blade between its outer ends, the depth of said yoke being sufficient to permit said blade to swing between the arms thereof, a U-shaped guard pivotally secured to said yoke and having its body to one side thereof and engaging with said blade to normally prevent movement of the latter, a portion of said guard being extended to the opposite side of said yoke, a part of said extended portion being outstruck and engaging the rear edge of said yoke to normally prevent movement of said guard.

7. A razor, including, in combination, a handle, a blade connected therewith and a guard for said handle, said guard presenting a series of teeth at its outer edge, certain of said teeth extending rearwardly, and said blade being formed with recessed portions cooperable with said rearwardly-extending teeth.

8. A safety razor, including, in combination, a handle, a guard, a blade position adjacent said guard, and a blade-retaining member connected with said handle, said member including a body formed with an opening, a tongue extending from said body and having a portion to extend into said opening, said blade being insertable between said tongue and body and being formed with an opening to be disposed in line with said first opening.

9. A safety razor, including, in combination, a handle, a guard, a blade disposed adjacent said guard and being formed with notches in its rear edge, a blade-retaining member connected with said handle and including a body having outstruck portions to enter the notches of said blade.

In testimony whereof I affix my signature.

SAMUEL SEGAL.
